Frederick W. Hartup, Covina, Calif., assignor to Modern Village Stores, Inc., a corporation of California

Application October 15, 1954, Serial No. 32,683

Term of patent 14 years

(Cl. D80—9)

FIG. 1.

FIG. 2.

To all whom it may concern:

Be it known that I, Frederick W. Hartup, a citizen of the United States, residing at Covina, in the county of Los Angeles and the State of California, have invented a new, original, and ornamental Design for a Check Stand or Similar Article, of which the following is a specification, reference being had to the accompanying drawing, forming part thereof.

Figure 1 is a perspective view of one side and end of a check stand showing my new design as viewed from a corner at the discharge end thereof;

Fig. 2 is a perspective view of the opposite side and the opposite end of the check stand as viewed from the diagonally opposite corner from that from which the view of Fig. 1 is taken; and

Fig. 3 is another perspective view of the check stand.

I claim:

The ornamental design for a check stand or similar article, substantially as shown.
